UNITED STATES PATENT OFFICE.

ALBERT RETZER, OF MILWAUKEE, WISCONSIN.

EGG CARTON.

Application filed March 23, 1923. Serial No. 627,029.

To all whom it may concern:

Be it known that I, ALBERT RETZER, a citizen of the United States, and resident of Milwaukee, in the county of Milwaukee and State of Wisconsin, have invented certain new and useful Improvements in Egg Cartons; and I do hereby declare that the following is a full, clear, and exact description thereof.

10 This invention relates to improvements in egg cartons.

The carton comprises two substantially similar mating sections, each having apertured inner walls for the reception of the 15 eggs, longitudinal flaps and partitions adjacent the apertures for bracing the outer, inner and side walls of the carton.

The primary object of the invention is the provision of a carton having two substantially 20 similar separable parts. When the eggs are being delivered to the housewife, half of the carton may be left having the eggs therein and the other half may be returned to the store. This half may be used 25 again, so that an economy may be effected in this way. The housewife may put the section containing the eggs into an ice box, or a nice suitable place, and the eggs are retained in position for convenient removal.

30 With half of the carton gone, the container will occupy but little space. The provision of a section which will serve in this manner as a dish is important and each section of the carton is made of the smallest amount 35 of material that will permit usage of a carton in this manner; that is, as a tray for facilitating the removal of the eggs. The two sections together form a perfect carton and there are few fold lines. Smallness in

40 the quantity of the material and the simplicity of the construction make possible the production of the novel carton at a very low cost.

An object of the invention is the protection 45 of the eggs at both ends, whereby possibility of breakage is eliminated. Longitudinal flaps are provided and partitions brace the outer wall from the inner wall and also the inner walls from each other. The 50 carton may be laid on a counter without danger of crushing the shells, as the partitions and flaps protect them against force lengthwise of the eggs. The partitions op-

erate, also, to prevent contact of one egg with another and serve in this way to prevent breakage. 55

An object of the invention is the provision of means for locking the flaps together, so as to impart rigidity and strength to each of the sections. 60

An object of the invention is the provision of a rubber band on each carton, secured at one end thereof. This serves as a convenient means for securing two sections together, as they may be stretched about them and effectually prevent separation. The bands serve, also, as a shock absorber. If a non-yielding retaining member, such as a string, were used, there would be no yield, so that when the carton is subjected 70 to shock, there would be danger of crushing the eggs. With the bands, however, a slight yielding of the rubber permits the taking up of shock and tends to eliminate danger of breakage. 75

With the above and other objects in view, which will appear as the description proceeds, the invention resides in the novel construction, combination and arrangement of parts substantially as hereinafter described 80 and more particularly defined by the appended claims, it being understood that such changes in the precise embodiment of the herein disclosed invention may be made as come within the scope of the claims. 85

In the accompanying drawings is illustrated one complete example of the physical embodiment of the present invention constructed according to the best mode so far devised for the practical application of the 90 principles thereof.

Figure 1 is a transverse section through a carton.

Figure 2 is a plan of the blank of a section, part being broken away, the line 1—1 95 indicating the plane on which Figure 1 is taken.

Figure 3 is a longitudinal sectional part of a carton.

Figures 4 and 5 are sections on the lines 100 4—4 and 5—5 respectively of Figure 3.

The upper section 10 comprises an outer wall 11, side walls 12 and 13, inner walls 14 and 15, and flaps 16 and 17. These walls are continuous and formed from a single 105 blank, shown in Figure 2. The ends of the

blank form flaps 16 and 17, the edges of which contact with the inner face of outer wall 11. The flaps are bent sharply with respect to the inner walls along lines 18 and 19 and the outer walls are directed sharply away from the inner walls along lines 20 and 21. The corner 22 between side wall 12 and outer wall 11 is rounded, as is also corner 23 between outer wall 11 and side wall 13. A row of partitions, 25, 26, 27 and 28 is cut in inner wall 14. The partitions are shaped similarly. Partition 25 terminates in a straight lower edge 28' and has curved side edges 29 and 30. A series of tongues 31 is formed, and are directed upwardly from inner wall 14. An end opening is provided in the inner wall at each of the partitions and the tongues border the opening and serve as a cushion for the egg, tending to prevent downward or sidewise movement thereof. The apertures conform to the shape of the egg. As previously stated, the various parts of each section are made from a single blank. When the section is in flat, or blank form, the tongues and the partition adjacent thereto completely fill the aperture, the tongues having edges contiguous to the edge 28' of the partition. Thus, there is no wastage of material in the making of the aperture. An economy in production is, therefore, effected. Partition 26 operates to protect the egg which is deposited thereagainst from contact with the egg which is deposited against partition 25, and the latter partition operates to prevent escape of the egg from the end of the carton. Any number of apertures may be provided in the inner wall 14, but preferably they are six in number. Partitions 25, 26 and 27 are disposed in the same direction from the lines at which they join the blank, as viewed from Figure 2. Partition 28, however, extends in an opposite direction. It results, therefore, that at each end of a row of apertures, a partition is provided, which prevents the escape of an egg from the carton at the end and also braces the carton at this point. It is not necessary, however, that a partition be thus formed at the extreme end of the carton. When the two sections are assembled, as shown in Figure 1, a complete carton is formed. As shown in Figure 1, partition 25 extends from the inner wall 14 to the outer wall 11 and braces the two walls apart. The egg is thus protected against transverse stresses. The lower section 10', shown in Figure 1, is, as stated, a duplicate of section 10. Partition 25' therein operates in precisely the same manner as partition 25. The inner portions of partitions 25 and 25' are immediately adjacent each other. The partitions operate, therefore, somewhat as a single unitary partition extending from

outer wall 11 to outer wall 11'. They serve, furthermore, as a brace between the outer walls. The inner portions of partitions 25 and 25' may be spaced ~~apart~~ longitudinally of the carton, if desired. They would still ⁷⁰ brace walls 11, 11'. Inner wall 15 is provided with a plurality of apertures, similar to inner wall 14, and has a row of partitions 33, 34, 35 and 36, similar to partitions 25, 26, 27 and 28. Partition 33, as shown ⁷⁵ in Figure 1, operates as a brace between the inner and outer walls.

The flaps and the partitions are operative, therefore, to protect the eggs against endwise stresses. If the carton is laid on a ⁸⁰ counter, there is no danger of cracking the eggs at their ends, since it would be necessary to move one of the outer walls towards the other, in order to exert pressure on the egg and movement of these walls towards ⁸⁵ each other is prevented by the partitions and the flaps.

When eggs are being delivered to a housewife, one of the sections of the carton may be removed. The eggs will then be carried ⁹⁰ in the other section. The empty section may be returned to the store and may be again used with another section to form another carton. Heretofore, when eggs have been delivered at a residence, it has been ⁹⁵ impractical to return the carton to the store. Thus, there was the loss of the value of an entire carton. With the return of half of the carton to the store, a decrease in the expense equal to one-half the cost of the carton occurs. Thus, an economy is effected. The section containing the eggs may be deposited by the housewife in any suitable place as, for instance, an ice box. It occupies a minimum of room and holds the eggs in position for convenient and immediate usage. It thus serves as a tray and as a tray, it is made of the smallest quantity of material that such an object could be made of and still be operative to maintain the eggs ¹⁰⁰ properly in position for usage.

To the outer face of outer wall 11 of section 10, a rubber band 36' is secured by means of staple 37. When the two sections are positioned as shown in Figure 1, the band is stretched about the carton and secures the two parts together, preventing movement of one section away from the other. Section 10', as described, is of the same construction as section 10 and is, therefore, also provided with a rubber band. Thus, a band is provided at each end of the carton and both ends of the carton are securely retained. The bands serve not only as a convenient securing means, but also as a shock absorber, as their thickness tends, in the first place, to space the outer walls of the carton from the counter, or other object on which the carton may be positioned and, in the second place, the elasticity ¹¹⁰ ¹²⁰ ¹²⁵ ¹³⁰

of the bands permits a slight spreading of parts. If a non-elastic member were wound about the carton, there would be greater danger of breakage, as rigidity of parts 5 would result. This rigidity is lessened by the yielding character of the band.

Flap 17 is severed along lines 38 and 39 to form a narrow strip 40 which extends from line 19 to the edge of the flap. This 10 strip is inserted through a slot 41 cut in flap 16 adjacent line 18. The strip 40 is then bent downwardly and lies along the surface of flap 16. It operates to prevent the flaps from moving upwardly and apart, 15 and serves to impart rigidity and strength to the section. It is operative both when the section is empty and when it is filled with eggs. The strip may be located immediately adjacent to the opening at partition 35, in which case the egg cooperates with the strip to prevent lateral movement thereof and to ensure a more reliable lock. The strip need not, however, be located at this point, since if it is positioned immedi- 20 ately adjacent to a partition, the partition will cooperate to prevent lateral movement. A second strip 42 is formed in flap 17 and is extended, as shown in Figure 5, through the aperture adjacent partition 26. The 25 strip is then downwardly directed adjacent flap 16. It locks the two flaps of the section together, both when the tray is empty and when it is filled with eggs. When it is filled with eggs, the contact of an egg 30 with the strip promotes further the reliability of the locking action, as it prevents possibility of removal of the strip. Either 35 of the strips 40 or 42 may be used alone instead of both together, if desired.

40 It is apparent that a carton has been provided of a special simplicity of construction, having few fold lines and a minimum number of parts.

I claim:

1. A carton open at both ends comprising an outer wall, a side wall continuous therewith, an inner wall continuous with said side wall and having apertures therein, a flap continuous with said inner wall, a second side wall continuous with said outer wall, a second inner wall continuous with said second side wall and having apertures therein, a second flap on said second inner wall and means for locking said flaps together. 45

2. A carton section comprising an outer wall, a side wall continuous therewith, an inner wall having apertures therein, a flap continuous with said inner wall, a second side wall continuous with said outer wall, a second inner wall continuous with said second side wall and having apertures therein, a flap continuous with said second inner wall and a strip formed in said second flap and extended into an aperture in said first 60 mentioned inner wall and downwardly directed to lock said flaps together. 65

3. A carton section comprising an outer wall, a side wall continuous therewith, an inner wall continuous with said side wall 70 and having apertures therein, a flap continuous with said inner wall, a second side wall continuous with said outer wall, a second inner wall continuous with said second side wall and having apertures therein, a 75 second flap continuous with said second inner wall and having a slot therein and a strip formed on said first mentioned flap extending through said slot and locking said flaps together. 80

In testimony that I claim the foregoing I have hereunto set my hand at Milwaukee, in the county of Milwaukee and State of Wisconsin.

ALBERT RETZER.
